UNITED STATES PATENT OFFICE.

HERBERT RAYMOND BARRETT, OF SOUTHPORT, AND KENNETH McCLYMONT WILSON, OF MANCHESTER, ENGLAND, ASSIGNEES TO THE PHOENIX MOTOR COMPANY, OF ALTRINCHAM, ENGLAND.

CARBURETER.

1,089,524.

Specification of Letters Patent. Patented Mar. 10, 1914.

Application filed November 6, 1911. Serial No. 858,867.

To all whom it may concern:

Be it known that we, HERBERT RAYMOND BARRETT and KENNETH McCLYMONT WILSON, both subjects of the King of Great Britain, residing, respectively, at 29 Park Crescent, Southport, in the county of Lancaster, England, and 15 Regent street, Chorlton-on-Medlock, Manchester, in the county of Lancaster, England, have invented certain new and useful Improvements in or Relating to Carbureters or Vaporizers for Internal-Combustion Engines, of which the following is a specification.

This invention relates to carbureters or vaporizers for internal combustion engines.

According to this invention, the carbureter or vaporizer is adapted by means of a rotatable choking plate to control the proportions of the fuel and air and to impart a swirling motion to the mixture to effect more perfect vaporization. The oil or fuel jet of the carbureter is associated with a number of tapered air passages and the rotatable choking plate, the desired control being readily effected by the operation of this latter member.

In order that the said invention may be clearly understood and readily carried into effect we will proceed to describe the same with reference to the accompanying drawings in which:

Figures 1 and 2 are views in vertical section illustrating a carbureter or vaporizer constructed according to this invention, a portion between the upper and lower ends being removed so as to show the essential parts more clearly. Fig. 2^a is a bottom plan view of the shutter sleeve. Figs. 3 to 5 are views showing three approximate positions of the choking plate on the oil jet and air passages.

The apparatus comprises a chamber *a* having a port *a'* in communication with the working cylinder, or the combustion chamber pertaining thereto, and adapted for receiving a sleeve or shutter *a²* arranged for rotatory movement by means of a handle *a³* or other device, the said handle being provided with suitable stops or guides for limiting its movement in either direction of setting. The sleeve *a²* is formed with an aperture *a⁴* which in a certain position of the sleeve is caused to register with the port *a'* in the chamber *a*. The fuel is supplied to the interior of the sleeve or shutter *a²*, which

serves as a mixing chamber for the air and petrol, by means of a jet arranged transversely or diametrically to the chamber *a* and the sleeve *a²*, the jet consisting of a plate *b* having a bar *b²* arranged across the same and formed with small or suitably proportioned spray holes *b³* for the discharge of the petrol or other hydrocarbon. Upon each side of this bar an opening *b⁴* is provided. The bar *b²* is formed with taper sides *b⁵* and the openings *b⁴* are also formed with taper or inclined sides or surfaces *b⁶* and the latter register with similar taper surfaces or passages *b⁷* formed in a base plate *c* to which the jet plate *b* and the chamber *a* are secured by screwed studs or the like. The fuel is admitted to the jet by means of a pipe or passage *c'* conveniently led into the base plate *c* and the bar *b²* of the jet. The sleeve or shutter *a²* serves as a means of regulating the port *a'* leading to the engine or the combustion chamber thereof and adjacent to the jet the said sleeve is provided with inwardly directed abutments or bosses *c²* between which and the jet a plate *c³* is placed same being carried by the sleeve *a²* and having an elongated opening *c⁴* therein formed with taper sides *c⁵* which are normally in line with the taper sides *b⁶* of the apertures *b⁴*, *b⁷* in the jet plate *b* and the base plate *c*. By turning the sleeve *a²*, the plate *c³* by means of the elongated opening *c⁴* therein, has the effect of restricting or cutting off the jet apertures *b³* and of regulating the air passages *b⁴* constituted by the side apertures in the jet plate *b* and the base plate *c*. The plate *c³* is preferably secured to the sleeve *a²* by an adjustable securing means, such as the studs *c⁶* which are adapted to engage with elongated openings or slots in the plate *c³* and allow of its adjustment relatively to the sleeve.

The jet may be constituted by inserting small perforated plates of brass or other suitable metal or material or by drilling minute holes. The jet may moreover be constructed in sections or in say two portions, the perforations being formed by making fine grooves in the meeting faces of the two parts.

The manner in which the air is supplied to the jet and the construction of the jet, hereinbefore referred to, have the effect of facilitating the use of heavy oils. The manner of choking the air by means of the taper

inclined passages and rotatory choking plate c^3 produces a swirling motion in the mixture, tending to more perfect vaporization. The elongated character of the opening c^4 in the air choking device c^3 permits of a partial restriction of the air supply with the jet fully exposed as shown in the dotted position of the opening Fig. 3, or of a full supply of air being admitted to the engine 10 with the jet in the exposed condition when the opening is in the position shown in full lines in Fig. 3. Approximate positions of the choking device are shown in the drawing, Fig. 3 showing the position of the device when the throttle is open and partially closed, Fig. 4 when the throttle is half closed, and Fig. 5 when the throttle is fully closed.

By means of the herein described improvements a more perfectly variable carbureter is produced than has been heretofore proposed for use with oils or hydrocarbons.

What we claim and desire to secure by Letters Patent of the United States is:—

25 1. A carbureter or vaporizer for internal combustion engines, comprising in combination, a casing, a diametrical bar therein, a fuel jet in said bar, tapered air passages extending along and contiguous to the sides 30 of said bar, and a rotating choking plate for controlling the proportions of the constituents of the mixture and for imparting a swirling motion to the same.

35 2. A carbureter or vaporizer for internal combustion engines, comprising in combination, a casing, a tapered perforated bar, means for conducting the oil to said perforated bar, tapered air passages adjacent the sides of said perforated bar, a rotating 40 sleeve in the casing, and a choking plate carried by said rotating sleeve, said plate

having an aperture formed with tapered sides.

3. Carbureter or vaporizer for internal combustion engines comprising in combination 45 a casing, a tapered perforated bar, means for conducting oil to said perforated bar, tapered air passages adjacent to said perforated bar, a rotating sleeve in the said casing which is adapted to serve as a mixing chamber, a port in said sleeve for controlling the inlet to the engine, a choking plate carried by said rotating sleeve, and having an aperture formed with tapered sides. 50

4. Carbureter or vaporizer for internal 55 combustion engines comprising in combination a casing, a diametrical bar therein, a fuel jet in said bar, a plurality of tapered air passages, a rotating sleeve within said casing, and a choking plate adjustably mounted on said sleeve for controlling the proportions of the constituents of the mixture and for imparting a swirling motion to the same. 60

5. Carbureter or vaporizer for internal 65 combustion engines comprising in combination a casing, a tapered perforated bar, means for conducting oil to said perforated bar, tapered air passages adjacent to said perforated bar, a rotating sleeve in the said 70 casing which is adapted to serve as a mixing chamber, a port in said sleeve for controlling the inlet to the engine, a choking plate adjustably mounted on said sleeve and having an opening formed with tapered sides. 75

In testimony whereof we affix our signatures in presence of two witnesses.

HERBERT RAYMOND BARRETT.
KENNETH McCLYMONT WILSON.
